UNITED STATES PATENT OFFICE.

TARGE G. MANDT, OF STOUGHTON, WISCONSIN.

WAGON-STANDARD.

SPECIFICATION forming part of Letters Patent No. 391,256, dated October 16, 1888.

Application filed March 16, 1888. Serial No. 267,325. (No model.)

To all whom it may concern:

Be it known that I, TARGE G. MANDT, a citizen of the United States, and a resident of Stoughton, in the county of Dane and State of Wisconsin, have invented certain new and useful Improvements in Wagon-Standards; and I do hereby declare that the following is a full, clear, and exact description of the invention, which will enable others skilled in the art to 50 which it appertains to make and use the same, reference being had to the accompanying drawings, which form a part of this specification, and in which--

Figure 1 is a perspective view of my improved wagon standard as it appears upon the 55 end of the bolster. Fig. 2 is a perspective detail view of the standard removed from the bolster. Fig. 3 is a cross-section through the standard and one of its rings or eyes, and Fig. 60 4 is a detail view of one of the said rings or eyes detached from the standard.

Like letters of reference denote corresponding parts in all the figures.

My invention has relation to wagon-stands (sometimes called "bolster-stakes") made of metal; and it consists in the improved construction and combination of parts of a wagon-standard of that class, as will be hereinafter more fully set forth.

75 In the accompanying drawings, the letter A designates one end of a wagon-bolster provided with my improved standard or stake. The latter consists of a bar of iron or steel rolled so as to form a flat part or face, B, which faces the wagon-box, and a longitudinal rib, C. The lower part of the standard is provided with the usual tenon, D, the lower part of which is rounded and screw-threaded to receive a nut, E, whereby the standard is held in place after 80 the part D has been inserted through the usual aperture in the bolster. The upper end or top part of the flat face C is curved outwardly, as shown at F, and upon the rib C are bolted, a suitable distance apart, two or more eyes, (denoted by the letters G G,) which are of the peculiar shape shown in the drawings—that is to say, each of these eyes (which are by preference made of malleable cast-iron) consists of a circular part, H, and a flat part, I, forming 85 approximately a square corner, J. The part nearest this square corner is enlarged, as shown

at K, to adapt it to be bored through to form a bolt-hole, L, without weakening the metal too much. The square part of the eye G fits into the square corner formed by the face and 55 rib of the standard, and the eye is held in place by means of a bolt or rivet, M, inserted through the hole L and through a corresponding hole in the rib.

It will be seen that the eyes G may be attached to either side of rib C, according to whether the standard is to be used on the right or on the left side of the wagon, and it will further be seen that the enlarged or squared 60 part or corner J, by bearing against the inner side of the face and one side of the rib, prevents the eye from turning after the same has been fastened by means of the bolt or rivet M.

In order to fix the standard firmly in its position upon the bolster, I employ a pair of metallic braces, N N, the upper ends of which are fastened by a single bolt, O, to opposite sides of the rib C, while the diverging lower ends of 70 said braces are fastened by bolts, screws, or other suitable means to opposite sides of the 75 end of the bolster, as clearly shown in Fig. 1 of the drawings.

From the foregoing it will be seen that this makes a very light but strong standard, adapted to resist lateral pressure, and adapted to receive extension-stakes, which may be inserted 80 through the eyes G G in such a manner that the lower parts of said extension-stakes will be firmly braced against the corner formed by the flat face-plate and its rearwardly-extending rib. By rounding the upper part of the flat face-plate B outwardly the wagon-box may readily be inserted upon the bolster without catching against the top of the standard, and the peculiar construction of the eyes G, as 85 hereinbefore set forth and illustrated in the drawings, not only enables these eyes to be used on either side of the central rib, but also holds them firmly in place, so that they cannot turn or tilt out of their proper horizontal 90 position.

Having thus described my invention, I claim and desire to secure by Letters Patent of the United States—

The combination, with the wagon-standard 95 or bolster-stake consisting, essentially, of a flat face-plate and a rearwardly-extending rib,

of one or more eyes for holding the extension-stakes, said eyes having an enlarged angular corner-piece adapted to fit into the corner formed by the face-plate and its rib and to be held securely in position by means of a bolt or rivet inserted through the enlarged square part of the eye and the rib of the stake, substantially as shown and set forth.

In testimony that I claim the foregoing as my own I have hereunto affixed my signature in presence of two witnesses.

TARGE G. MANDT.

Witnesses:

THORVALD C. LUND,
OSWALD F. KROPP.
